W. SCHWEITZER & H. H. LABADIE.

SAMPLE CARRYING CASE.

APPLICATION FILED MAR. 18, 1912.

1,082,976.

Patented Dec. 30, 1913.

FIG. 2.

UNITED STATES PATENT OFFICE.

WILLIAM SCHWEITZER AND HARRY H. LABADIE, OF CHICAGO, ILLINOIS.

SAMPLE-CARRYING CASE.

1,082,976.

Specification of Letters Patent. Patented Dec. 30, 1913.

Application filed March 18, 1912. Serial No. 684,489.

To all whom it may concern:

Be it known that we, WILLIAM SCHWEITZER and HARRY H. LABADIE, citizens of the United States, and residents of Chicago, in the county of Cook and State of Illinois, have jointly invented certain new and useful Improvements in Sample-Carrying Cases; and we do hereby declare that the following description of our said invention, taken in connection with the accompanying sheets of drawings, forms a full, clear, and exact specification, which will enable others skilled in the art to which our said invention appertains to make and use the same.

This invention has general reference to sample carrying cases; and it consists, essentially, in the novel and peculiar combination of parts and details of construction, as hereinafter first fully set forth and described, and then pointed out in the claim.

In the drawings already referred to, which serve to illustrate this invention more fully, Figure 1 is an end elevation of the open case showing the sample-receiving trays in extended position. Fig. 2 is an end elevation of a modified form of a sample carrying case, one end of the case being removed showing the case proper in section. Fig. 3 is an end view of the same.

Like parts are designated by the same characters and symbols of reference in all the figures.

The object of this invention is the production of an efficient, serviceable, and very compact sample carrying case, in which link-connected trays are employed to receive the samples of merchandise that are to be carried by salesmen, solicitors and commercial sales travelers, to be shown to prospective customers. These trays, in folded up condition, are superposed in a tier or tiers, and inclosed in a case, which when open, permits the trays being horizontally extended to disclose their contents.

A, in the drawings designates the case proper. It is, in the present instance, constructed to receive but a single set or series of superposed trays B, which trays are connected, one to the other, by links C, C', as will hereinafter more fully appear. The body of this case is preferably made of wood which is externally and internally covered, the outer covering being usually leather, canvas or other suitable fabric, the inner lining being cloth, paper, or other similar cheaper material. This body comprises a

base and a cover, the base being constructed of a bottom 12, a rear side 13, a narrow front portion 14, and two ends 15, 15^a. These ends extend from the upper end of the rear wall 13 diagonally downward to the upper margin of the narrow front portion 14. The cover D, for this base is constructed substantially the same as the base portion, but reversed, that is to say, the portion 16 of the cover, answering to the bottom 12 of the base, forms the top of the cover; while the sides 17, corresponding to the rear or back wall 13 of the base, constitutes the front wall of the cover, the ends 18, 18^a, of the cover being of the same shape as the ends of the base so that the joints of the cover and base are diagonally disposed.

The cover D, is attached to the base by suitable hinges 19, located at the upper margin of the back wall 13, and the lower margin of the rear wall 20 of the cover D, as clearly illustrated in the drawings; and it is locked to the base by suitably constructed snap locks 21, secured to the narrow front portion of the base and coacting with members 22, fastened to the margin of the front wall of the cover D.

A handle E, Fig. 1, fastened to the top member of the cover D, affords convenient means for carrying the complete case with its contents.

In the lower part of the base there are two transverse walls 23, 23, spaced from the inner surfaces of the ends 15, 15^a, of said base, and at the outer upper margins of these walls there are secured metallic bars 24, and to each of these bars 24 are pivotally connected two links C, C', at one of the latter's ends, the ends of the links C engaging studs 25 or pivots 26 at the outer ends of the bars 24, and the links C' engaging the pivots 26, located in the middle of said bars 24. The upper ends of the links C, C', connect the lowermost tray B to the base in the following manner: At the upper margin of each end 27, of this tray B, there is secured a bar 28, and the upper end of the link C is pivoted to the middle of this bar upon the pivot 29, while the upper end of the link C' is pivoted upon a pivot 30, located at the rear end of said bar 28. The trays B', B², B³, and so forth, are all connected by links to the next lower tray in the same manner as the tray B is connected to the base, so that by taking hold of the uppermost tray and pulling on the same outwardly, all the trays

will move horizontally to submit their contents to inspection.

It will be observed that when the cover D is turned into open position shown in Fig. 1, 5 this cover will extend rearwardly from the base and thereby approximately balance the case with its trays in extended position; but, in order to sustain these trays in this extended position, especially when the samples therein are comparatively heavy, we 10 secure, preferably to the middle tray, one or more supports F, which supports are permanently fastened to the front wall 31, of said tray and extend downwardly to the 15 narrow front wall 14 of the base, and then by a horizontal portion 32, over this front wall, and then downwardly and in front of this wall 14. In this manner, the trays may be extended when the cover D is open, with- 20 out the supports interfering with any portion of the base.

We have illustrated in Figs. 2 and 3 a modified form of construction of the supporting means for the trays. In this case, 25 the support F is a straight bar fastened at one end to the tray and extending downwardly to the bottom of the base. The narrow front portion 14 of the base is hinged thereto at 33, so as to swing outwardly and 30 downwardly to permit the support F to pass out of the base when the trays are being extended.

While we have heretofore described the 35 preferred embodiment of our invention with special reference to the specific construction

of the case proper in which the link-connected trays are mounted, we desire it to be understood that we do not wish to confine ourselves to this particular type of cases, which might be of the so-called telescopic 40 variety, as indicated in Fig. 3, or of any other design, so long as the case is so constructed that the supports which are fixedly secured to the tray, may pass out of the case when the trays are being extended without 45 manipulating said support.

Having thus fully described this invention, we claim as new and desire to secure by Letters Patent of the United States—

A sample carrying case including a base, 50 a cover for said base, a series of superposed, link-connected, trays mounted in said base, and a support for said trays, said support being a bar fixedly secured to one of said trays and extending downwardly to the 55 front wall of said base, thence over the upper edge of said front wall and thence downwardly in front of said front wall to permit said trays to pass out of said base when said trays are being extended without manual 60 manipulation of said support, as specified.

In testimony whereof we have hereunto set our hands in the presence of two subscribing witnesses.

WILLIAM SCHWEITZER.
HARRY H. LABADIE.
